UNITED STATES PATENT OFFICE.

JOSEPH W. ANTHONY, OF LYNN, MASSACHUSETTS.

FOLDING MACHINE.

Application filed April 16, 1926. Serial No. 102,538.

This invention relates to folding machines especially adapted to fold at one operation all sides and the corners of book covers of varying dimensions, although it is not limited to this use exclusively.

In general, the machine embodying this invention is constructed on the principles illustrated in my Patent No. 1,477,745, dated December 18, 1923.

One of the objects of the present invention is to provide a folding machine of the general type above set forth wherein the operative components are inclined at such an angle with the horizontal that an operative can insert cover-blanks into and remove the folded blanks from the machine readily and wherein the folding space in the machine is relatively unobstructed, so that an operative can readily watch the operation of the folding elements.

A further object of the invention is to provide means to hold the blank securely in inclined position within the folding space to prevent the blank from sliding downwardly therefrom, until the folded elements have been moved into operative and holding engagement with the blank.

A yet further object of the invention is the provision of an improved construction which readily permits adjustments and changes of positions of the various elements of the machine for the folding of blanks of different dimensions.

The folding machine embodying the present invention is particularly adapted for the forming of round corners on the folded cover; and one of the objects of this invention is the provision of means whereby round corners of varying dimensions can be formed on book covers.

A further object is generally to improve the construction and operation of folding machines.

Fig. 1 is a side elevation of the folding machine embodying this invention.

Fig. 2 is a plan view of the machine of Fig. 1.

Fig. 3 is a vertical sectional elevation along line 3-3 of Fig. 2.

Fig. 4 is a plan view of the bed of the machine along line 4-4 of Fig. 3, certain of the parts being omitted to illustrate more particularly the mechanism for reciprocating the side and corner wipers.

Fig. 5 is a plan detail of the bed of the machine with the presser head and associated elements removed.

Fig. 6 is a plan detail of the bed of the machine illustrating more particularly the adjustable die bars which define the folding space and the sides of the folded cover.

Fig. 6^a is a perspective detail illustrating the adjustable support for a horizontal die bar.

Fig. 7 is a perspective detail illustrating the round corner defining means.

Fig. 7^a is a perspective detail illustrating the manner of attaching a filler bar to a die bar.

Fig. 8 is a perspective detail of a round corner block.

Fig. 9 is a plan detail of the round corner of a forming plate and illustrating the construction thereat for forming smooth round corners.

Fig. 10 is a side elevation of the corner of the forming plate illustrated in Fig. 9.

Fig. 11 is a plan view of a forming plate.

Fig. 11^a is an end detail of a forming plate, and its adjustable connections with the presser head.

Fig. 12 is an end view of a reciprocating member for a corner wiper and illustrating more particularly the adjustable connections between the wiper and its actuating member, to provide for the folding of materials of varying dimensions.

Fig. 12^a is a view similar to Fig. 12 but illustrating the construction for a side wiper.

Fig. 13 is a detail along line 13-13 of Fig. 1 and illustrating particularly the clutch mechanism for starting and stopping the operation of the machine.

Figs. 14 through 18 are details illustrating the relative positions of the blank and folding elements in the successive steps of the folding operation.

Fig. 19 is a detail illustrating the connection between the material supporting table and the oscillatory cam ring for raising and lowering the table.

Fig. 20 is an enlarged vertical sectional detail of the mechanism for holding the blanks in the folding space before the folding operation is started.

Fig. 21 is a plan detail of a cam block and associated mechanism for controlling the operation of the forming plates and for

holding the forming plates in their extended position against the wiping action of the wipers.

Fig. 22 is a plan view of the sliding interlocking connection between the stationarily-supported and vertically reciprocable sections of the operating rod for the forming plates.

Fig. 23 is a plan view of the adjustable pressure frame.

Fig. 24 is a sectional elevation along line 24-24 of Fig. 23.

Fig. 25 is a perspective detail illustrating the corner-construction of the pressure frame.

Fig. 26 is a detail illustrating the swivel connection between the pressure frame and a pressure-screw.

As here shown, the machine embodying this invention consists of a bed 10 which is provided with an inclined front face 12 on and above which the operative elements of the folding machine are disposed in inclined position and conveniently accessible to an operative sitting in front of the machine to place blanks therein and to withdraw the folded covers. The bed 10 is provided with a rearwardly disposed horizontal face 14 which forms a support for the driving mechanism.

The folding elements of the machine include a yieldingly mounted table upon which the blank is placed and retained during the folding operation. A clamping or presser plate is carried by a vertically reciprocable presser head disposed above the table and is adapted to be moved downwardly to clamp the material onto the table during the folding operation. Forming plates are also carried by the presser head and are movable downwardly therewith and are extensible to define the line of fold. Side and corner wipers are disposed about the table and are adapted to be moved inwardly and to fold the edges of the material over upon the forming plates. The forming plates are adapted to be retracted from under the folded material and the yieldingly-supported table and the wipers are adapted to press the folded edge onto the body of the blank to cause the previously applied adhesive to cement the folded edge to the blank-body. The work supporting table, the wipers and the operating mechanisms thereof are carried by a base plate 16 which is secured to the inclined face 12 of the bed 10. Said base plate is provided with an opening 18 in the middle thereof around which are disposed a plurality of upstanding posts 20. A second and concentric set of posts 22 are similarly extended upward from the base plate 16 in radial line with and spaced from said inner posts 20 to provide an annular guide groove in which a cam ring 24 is disposed for oscillatory movement. Aligned grooves

26, see Fig. 12, are formed in the upper faces of each set of outer and inner posts to form guideways in which slide blocks 28 for operating the wipers are disposed. Plates 30 are secured to said posts and are extended over said grooves to retain said blocks 28 in operative position in said grooves. Said cam ring 24 is provided with a plurality of cam slots 32 in its upper face and said slide blocks 28 are provided with depending cam-followers comprising pins 34 on which rolls 36 are journaled. Said rolls are received within the cam slots of the ring so that as the ring is oscillated throughout a suitable angle each slide block is correspondingly reciprocated. The arrangement of the cam slots is such that the diagonal cam blocks, which are adapted to operate the corner wipers, are moved inwardly shortly after the other slide blocks have been correspondingly moved.

Said cam ring is reciprocated by means including a gear sector 38 which is bolted or otherwise secured to the uppermost portion of the cam ring and is adapted to be in engagement with a reciprocable rack hereinafter to be described.

The cover-blank is adapted to be supported, during the folding operation, upon a yieldingly-supported table which is supported in parallel relation with and above the inclined base 16. Said table includes a flat plate 40 which is secured by screws 42 to the upper face of a bar 44. Said bar is provided at its ends with two depending rods 46 which are slidably received within bosses 48 of a plate 50. Compression springs 51 are disposed about said rods 46 above said bosses 48 and are adapted to bear upon said bosses and said bar 44, whereby yieldingly to support the table. The lower ends of said rods are screw-threaded and check nuts 53 adjustably received thereon are adapted to engage said plate 50 and thereby define the elevated position of said table. Provision is made for supporting various sizes of cover-blanks by removing a table plate 40 and substituting therefor one of dimensions which are suitable for the specific size of blank to be folded. Said plate 50 is secured to a cylindrical hub 52 which is carried by a bar of a table supporting frame 54 which, as shown in Fig. 3, is disposed above the previously described cam ring and slide blocks. Said hub 52 has a screw-threaded extension 56 which is extended downwardly through an aperture in said bar 54 and a spanner nut 58 is screw-threaded on said extension whereby to clamp said hub removably to said bar 54. Said hub 52 may be provided with pins 60 which are received in holes 62 of said bar 54 to preserve the angular setting of said hub.

Said table is adapted to be reciprocated above said base 16 for the purpose of press

ing the folded edges of the cover against the under side of the wipers. For this purpose, the table support 54 is provided with a plurality of depending lugs 64, which lugs, see 5 Figs. 19 and 4, are closely spaced about the outer periphery of the cam ring 24. Said cam ring is provided with suitably shaped cam slots 66 in its outer periphery and said lugs are provided with cam-followers comprising pins 68 on which rollers 70 are loosely received within said cam grooves. It is apparent that as said cam ring is reciprocated the table supporting frame and the table will be correspondingly reciprocated 10 above the base 16. Said frame is guided for reciprocatory movement by pins 71.

Said table is disposed within what may be considered a die frame, which bounds the folding space, and the blank is adapted to be forced down into the folding space and the edges of the blank are adapted to be wiped over the edges of the die during the folding operation. The die frame is adjustable so that the folding space therein can be 25 enlarged or diminished to provide for the folding of blanks of various dimensions. The die frame is composed of upper and lower horizontal flat bars 72 and 74 respectively and right and left vertically disposed 30 flat, or cross, bars 76 and 78, which bars are disposed beneath and are carried solely by said horizontal bars 72 and 74. Said horizontal bars are provided with sets of parallel grooves 80 in their end-portions and 35 said vertical bars are provided with similar parallel and T-shape grooves 82 in their end portions. Corner plates 84 are disposed upon said horizontal bars and clamping bolts 86 are passed through said corner plates and 40 through the slots of both vertical and horizontal bars thereby to clamp all parts rigidly together. Said bars are adjustable inwardly and outwardly by a sliding movement of one upon the other when said bolts 86 are loose 45 whereby to provide for changes of dimensions of the folding space enclosed within said bars. Said horizontal bars are adjustably carried by the base plate 16. To this end, said base plate is provided with upstanding 50 posts 90 at the corners thereof. Said posts are provided with parallel slots 92 in their upper faces and plates 94 are secured to the upper faces of said posts and extend over said slots whereby to cooperate with said 55 slots to form T-shape grooves. Slide blocks 96 are slidably received on said plates 94 and have projections 97 in their lower faces which fit slidably into the spaces between said plates. T-shape clamping bolts 99 are 60 carried by said slide blocks 96 and have their heads received in grooves 92 whereby to clamp said slide blocks in any adjusted position. The opposite ends of said horizontal bars 72 and 74 are secured to the upper faces 65 of said slide blocks 96 by screws 100.

It is apparent that when said clamping screws 86 and 99 are loose, said horizontal bars may be adjusted toward and away from each other and said cross bars 76 may be correspondingly adjusted on said horizontal 70 bars whereby to vary the dimensions of the folding space bounded by said bars.

Means are provided to form round corners at the junction of said horizontal and vertical bars whereby to assist in the formation 75 of round corners on the folded cover. To this end corner blocks 102, best illustrated in Fig. 7, are disposed on said vertical bars 76 and 78 and against said horizontal bars; and are secured to said cross bars by screws 104 80 which are received adjustably in the slots 82 of said bars. Said corner blocks 102 are provided with arcuate faces 106 which have their edges 108 and 110 aligned respectively with the inner faces of said horizontal and cross bars whereby to form in effect a round corner which connects said bars. Round corners of various dimensions may be folded by providing a plurality of interchangeable blocks 102 which have various dimensions of 85 arcuate faces 106.

Since the upper faces of said cross bars 76 and 78 are under the horizontal bars, filler bars 112 are carried by said cross bars, in the space between said horizontal bars, and extend upwardly sufficiently to bring their top faces approximately flush with the upper faces of said horizontal bars so that the top faces of said filler and horizontal bars are in approximately the same plane. Said filler 90 bars have notched end portions which are adapted to fit snugly in the corner blocks 102 whereby to be retained removably in position. The edges 110 of said corner blocks are adapted to be approximately in line with the inner vertical spaces of said filler blocks whereby to form a smooth wall bounding the 95 folding space. A plurality of filler bars are adapted to be provided to correspond with the various widths of blanks to be folded.

The die frame is provided with top and bottom wipers 116 and 118 respectively and right and left side wipers 120 and 122 respectively. The top and bottom wipers 100 comprise flat plates which rest upon the upper and lower horizontal bars 74 and 72 respectively and are adapted to be reciprocated thereupon into and out of the folding space. The corner plates 84 are provided with 105 grooves in their under faces into which the ends of said wipers are slidably received and guided. Said right and left side wipers 120 and 122 comprise similar flat plates which are supported by and slide over the corner blocks 102 and filler bars 112. The corner 110 plates 84 are recessed to receive the ends of 115 said wipers.

Said corner plates are provided with corner wipers 124 which are adapted to be supported by and slide upon the horizontal bars 120 125 130

72 and 74 at a 45° angle therewith and said corner plates 84 are provided with grooves in their lower faces in which said corner wipers are received and guided for reciprocating movement.

The upper and lower wipers are detachably secured by screws 128 to the top faces of wiper carriers 130, which carriers have tapered side walls which are reciprocable in correspondingly shaped grooves 131 formed in the middle portions of the upper faces of said upper and lower die.

Filler blocks 127 are secured to the middle of the upper faces of the side die bars and are substantially flush with the top faces of said upper and lower die bars. Said blocks are provided with dove-tail grooves 132^a in their upper faces in which the side wiper carriers are slidable. The top faces of all wiper carriers are approximately flush with the top face of the die frame. The filler bars 112 are secured removably to the ends of said filler blocks by screws 113. Said wiper carriers, and the corner wipers, are connected with their respective slide blocks 28 by means which permit said carriers and corner wipers to be adjusted inwardly and outwardly toward and away from the middle of the folding space and operated in any adjusted position for the folding of blanks of varying dimensions. To this end, the slide blocks 28 for the side wipers are formed with T-shaped grooves 132, see Fig. 12^a, in their upper faces. Z-shaped supporting standards 134 are adapted to connect rigidly said blocks and wiper carriers. Said carriers are secured removably to the upper faces of said standards by screws 136. Said standards are secured adjustably upon said slide blocks 28 by means of bolts 138 and T-nuts 140, which nuts are received within the T-shaped grooves of said slide blocks. As thus arranged, said standards can be adjusted along the lengths of said slide blocks and secured in any adjusted position whereby to permit the side wipers to be suitably located for the folding of a selected blank. The adjustable connection between the corner wipers and their respective slide blocks is similarly provided except that the standards 134^a associated with said corner wipers are secured adjustably on the upper faces of adjustment-bars 142, which bars are provided with horizontally extended T-shaped slots 144 therein in which the clamping bolt and nut 146 for said standards 134^a are received. Said bars 142 are arranged approximately parallel with the horizontal line of the bed and are supported on spacer-blocks 148 above and are connected with the slide blocks 28 for the corner wipers by the bolts 150. The arrangement is such that said bars 142 can be adjusted along their respective slide blocks and the standards 134^a for the corner wipers can be adjusted on said

bars; and both may be secured in any adjusted position whereby suitably to position the corner wipers for the folding of a selected blank.

The forming plates and presser plate are carried by a presser head 152 which is reciprocably disposed above the folding space. Said presser head includes a supporting frame having a base plate 154 which is extended over the folding space from the rear portion of the machine. Said plate 154 is provided with an upstanding extension 156 at its rear end which is formed or provided with parallel V-shaped slides 158 at its opposite sides; and said slides are reciprocable in a plane perpendicular to the bed 16 in slideways 160 provided in the opposed ends of arms 162 of a bracket secured to the frame of the machine at the rear of and above the folding elements. The presser head includes a pair of opposed arms 164 which are bolted at their upper ends by bolts 166 to said supporting frame. Said arms are connected intermediate their ends by an integral cross-member 168 which is secured by a screw 170 to the base plate 154 of said supporting frame. Said arms 164 are outwardly divergent at an angle of 45° with the vertical center of the machine, below said cross member 168, and are integrally connected with arms 172. The frame is also provided with upper and similarly disposed arms 174, which arms provide supports for the forming plates. The under faces of said upper and lower arms 172 and 174 are formed with dove tailed slots 176 which extend at right angles with each other; and slide blocks 178 are reciprocably received within said grooves. The lower faces of said blocks are extended below said arms and are formed with tapered parallel side walls 180 which are received within complementary slots 184 in adjustment blocks 182 see Fig. 11^a. Said adjustment blocks are also provided with ribs 186 which are disposed below and at right angles to said grooves 184, on which ribs the forming plates are adapted to be slidably received.

There are four forming plates, all similar in construction which, see Fig. 11, are composed of thin sheet material provided with side-extension 188 disposed at right angles and the rounded corner 190 connecting said side-extensions. Said plates are suitably secured to brackets having the upstanding walls 193 and outstanding supporting feet 194 which are integral and at right angles with said upstanding walls. Said supporting feet are formed or provided with grooves 196 having parallel side walls and arranged parallel to one of the side-extensions of the forming plates and in which grooves said ribs are adapted to be slidably received. Clamping bolts 200 are passed through the slots 198 in the feet of the forming plates 130

and the apertures 202 in the adjustment blocks and also through slots 204 in the slide blocks 178, whereby to secure all fixedly together in some relatively adjusted position.

- 5 The above construction provides an arrangement whereby the forming plates can be moved outwardly and inwardly with respect to the folding center of the machine whereby to adjust the forming plates to operate 10 upon blanks of differing dimensions in an obvious manner.

The contiguous edges of the adjacent forming plates are adapted to overlap in all positions thereof, whereby to define a continuous line of fold.

- 15 The slide blocks 178, and consequently the forming plates, are adapted to be reciprocated outwardly and inwardly by means of a slide block 206. Said block rests upon the 20 base plate 154 of the supporting frame, between and above the forming plates, and is reciprocated by means hereinafter to be described. Said block is provided with a slot 208 therein through which a screw 210 fixed 25 to said base plate is passed whereby to restrain said block from detachment with the supporting frame. Links 212 are pivotally connected at their upper ends with said block and at their lower ends are pivoted on screws 30 214 fixed in the lower slide blocks 178, so that, as said block 206 is reciprocated back and forth, said lower slide blocks 178 with their attached forming plates are also reciprocated, thereby to extend and retract the 35 forming plates. Links 216 are pivoted at 218 to the upper slide blocks 178. The lower ends of said links are pivoted to levers 218, which levers are suitably pivoted at 220 intermediate their ends to the arms 164 of the 40 presser head. The inner ends of said levers are loosely pivotally connected with the slide block 206 by means of screws 222 which are extended through slots 224 of said levers. As thus arranged, the reciprocatory movement 45 of said slide block 206 also serves to reciprocate the upper forming plates; and all forming plates are thus arranged to be moved outwardly and inwardly together.

- The above described adjustable supports 50 for the forming plates permit operation upon blanks having a moderate range in dimensions. For operation upon blanks of greatly differing dimensions one set of forming plates is adapted to be removed from the 55 machine and replaced by another set of forming plates which have dimensions suitable for operation on the selected blank.

- Said forming plates are disposed immediately above a presser plate 226, which is 60 carried detachably at the lower end of a post 228 secured in and dependent below the base member 154 of the supporting frame. Said presser plate is adapted to be lowered by movements of the presser head into contact

with the blank to press it onto the support- 65 ing table and to hold it in place thereon during the operation of the forming plates and the wipers.

The forming plates are adapted to be reciprocated by a rod or shaft 230 which is 70 mounted for sliding movement in the extension 156 of the supporting frame and is attached at its forward end to the slide block 206. Said shaft 230 is actuated by means including a reciprocable shaft 232 which is 75 slidable in the fixed frame of the machine. Since said shaft 230 is carried by the reciprocable presser head, means are provided to slidably connect said shaft 230 and 232 to permit movement of said shaft 230 while 80 maintaining the positive connection between the two shafts operative at all times. To this end, the forward end of the shaft 232 is provided with a block 234 which block is provided with a vertically extended dove tailed 85 groove 238 in its front face. The rear end of said shaft 230 is provided with a block 240 which is provided with a tongue 242 is slidable in said groove. As thus arranged, 90 said shafts are positively connected, or are interlocked, for conjoint reciprocatory movement regardless of the position of the presser head.

The presser head is reciprocated by means of a lever 244 which is disposed above said 95 presser head and is pivoted intermediate its ends to upstanding lugs 246 of the frame of the machine. The forward end of said lever is pivotally connected to a yoke 248 which is 100 adjustably screw-threaded into the vertical extension 158 of the supporting frame of the presser head whereby to reciprocate said frame. The rear end of said lever 244 is pivotally connected loosely with a slide block 105 250 which is slidable in a guide slot 254 of the frame of the machine. Said slide block is adapted to be reciprocated whereby to reciprocate said lever and consequently the presser head.

All of the folding elements are adapted to 110 be actuated by means of a vertical frame 256. Said frame is slidable on vertically spaced cylindrical rods 258 which are fixed in and are horizontally extended between side arms 260 of the machine-frame at the rear and upper ends thereof. Said vertical frame is provided with an inclined wall 262 which is disposed at the rear of said slide block 250 and supports a cam block 264 for operating said slide block 250. Said cam block is provided 115 with a cam groove 266 of approximately Z-shape and said slide block carries a cam-follower including a cam roller 268 which is received within said slide. The shape of 120 said cam groove is adapted to be such that, as said frame 256 is reciprocated, the presser head is held without motion during the first and last parts of the stroke of the frame

and is moved downwardly or upwardly, as the case may be, during the intermediate part of the movement.

- Said frame is also provided with a second inclined wall 270 which supports the cam block 272 for operating the forming plates. Said cam block, illustrated more particularly in Fig. 21, is provided with a cam slot 274 in which is received the cam-follower comprising a roll 276 carried by and depending from the shaft 232 associated with the forming plates. Said cam slot 274 is in effect similar to the cam slot in the cam block 264 illustrated in Fig. 3, modified however in a manner to prevent the forming plates from being retracted by the pressure exerted upon them by the wiping movement of the side wipers as they wipe over the edge of the blank on top of the extended forming plates.
- To prevent such undesired movement of the forming plates, a bar 278 is slidably disposed in said cam block. The forward end of said bar is provided with an inclined projection 280 which is approximately parallel with the inclined wall 282 of the cam slot. Said bar is maintained yieldingly in the position shown in Fig. 21 by means of a compression spring 284 which bears against said bar 278 and also against a bracket 286 carried by the cam block, thereby to define a more or less Z-shaped cam slot. When said cam block is moved toward the right, Fig. 21, the cam roller 276 is brought into engagement with the projection 280 of said bar and serves to move said bar towards the left against the action of said spring without movement of the shaft 232 associated with said cam roller. When, however, said projection 280 is moved against the wall 288 of the cam block, it is held from further movement and the cam roller and its associated shaft are consequently forced to move along the inclined face of said projection whereby to urge the forming plates outwardly.
- When the cam roller reaches the left hand end of the cam slide, it is free from the bar 278 and its projection. The spring 284 consequently presses said bar inwardly into the cam slot to occupy the position illustrated, in which position it is disposed behind said cam roll and thereby restrains it and the forming plate against backward movement. When the cam block 272 is moved in the opposite direction, or towards the left, the roller is brought against the inclined face 282 of the cam slot and is consequently moved rearwardly whereby to retract the forming plates without acting on said bar 278.
- The operating frame 256 is provided at its lower end with a rack 290 which is in mesh with the gear sector 38 carried by the cam ring 24. The reciprocatory movement of said operating frame consequently serves to reciprocate said cam ring in timed relation

with the movements of the presser head and forming plates.

The operating frame is reciprocated by means of a cam 292 fixed to a horizontal shaft 294 journalled in a pedestal 296 supported on the horizontal shelf 14 of the bed of the machine. Said cam is provided with a cam groove 300 in which a cam roller 302 carried by the operating frame 256 is received; and the shape of the cam groove and its arrangement is such as to provide for proper reciprocatory movement of said frame. Said shaft 294 is driven through small and large helical gears 304 and 306 by a pulley 308 which may be belted to any suitable source of power, not shown. Said large gear 304 is loosely mounted on said drive shaft 294 and means under the control of an operative are provided to connect said gear with and disconnect it from driving relation with said shaft. Said means comprises a clutch, see Figs. 3 and 13, including a hub 310 fixed to said shaft. Said hub is provided with a sliding pin 312 which is adapted to slide through an annular groove 314 in said hub and into a recess in the gear 304 whereby to lock the gear to the hub and consequently to the drive shaft, following more or less common practice. Means are provided to control the movements of said pin, whereby to operate the clutch. Said means includes a sliding plate 316 which is disposed mainly beneath said hub and is provided with arms 318 and 320 which are disposed on opposite sides of said hub and are provided with opposed wedge shaped faces 322 and 324 which are adapted to engage with an abutment of said pin and retract it from engagement with said gear in a more or less usual manner, whereby to bring the drive shaft and associated mechanism to rest. Said plate 316 is adapted to be reciprocated by means of a slide plate 326 which is connected through a link 328 with a pedal 330, by which it is adapted to be moved downwardly, under control of an operative, and is adapted to be retracted by a tensile spring 332. Said slide plate is provided with an inclined cam slot 334 in which is received a pin 336 carried by said clutch 316. When the clutch pedal is depressed, it serves to move the clutch plate toward the right, Fig. 13, thereby to withdraw the arm 318 from holding engagement with the clutch pin so that the pin is moved by the action of a spring, not shown, into engagement with the gear thereby to cause the drive shaft to rotate. If the treadle is immediately released, the drive shaft is caused to make one complete revolution and perform an entire folding operation. If, however, the clutch pedal is maintained depressed, the drive shaft is disconnected from the gear at the end of a half revolution by the arm 320. The purpose of this arrangement

ment is to permit the machine to be stopped momentarily in such position that the folded edges of the material are pressed by the supporting table against the under sides of the extended wipers for the purpose of insuring a bond of the cement-covered folded edge with the main body of the cover. When the pedal is released, the drive shaft makes a second half revolution to complete the folding operation.

To take care of the surplus material at the round corners of the fold, and to lay the pleats evenly, the forming plates are provided with a thickened section at their 15 round corners formed by attaching a thin plate 340 to the top faces of the forming plates. Said plates may have more or less parallel side edges 342 which are bevelled off to form a smooth junction with the forming plates. The corner wipers are adapted to wipe the material at the corner of the blank over said plates 340 and the thickness of the forming plates at the corners is adapted to be such as to take care of the surplus 20 material at the corner fold. It is found that, with this arrangement, the material at the corners folds down in even pleats and presents a smooth and symmetrical appearance.

30 Due to the inclination of the folding elements of the machine, means are provided to hold the blank in position between the elements until the presser head moves the blank downwardly and into contact with the supporting table. Said means includes a 35 rod 344, Figs. 1 and 20, which is slidable in the supporting hub of the table and terminates immediately beneath said table. Said rod is provided with a cross bar 346 at its 40 upper end which carries pins 348 at the ends thereof. Said pins are normally disposed below the top face of said table but are adapted to be moved upwardly through apertures in said table to press the cover blank 45 against the bottom of the presser plate and to hold it firmly against the presser plate as said presser plate moves downwardly to bring the material upon the table. The movement of said rod 344 is under control 50 of the operative by means of a lever 350 which is carried by the frame of the machine in position to be engaged by the knee of the operative. Said lever is connected through suitable means to a second lever 55 352 disposed to engage the lower end of said rod 344 and move it upwardly. A friction pin 354 is urged by a spring 356 to bear against said rod and to hold it frictionally in its raised position. The downward movement 60 of the presser head serves to restore the rod and associated levers to their normal position.

In the operation of the machine, the presser head, with the forming plates extended, is moved downwardly to clamp the

blank onto the supporting table and to carry the blank downwardly into the die frame and into a position illustrated in Fig. 15. The forming plates and presser head are then held stationary while the side wipers 70 are extended to fold the edge of the material over upon the forming plates, as illustrated in Fig. 16. The forming plates are then withdrawn and the presser head is retracted slightly whereby the blank-supporting table operates to press the folded edge of the blank against the lower faces of the wipers, as illustrated in Fig. 18. The wipers are then withdrawn and the presser head is raised upwardly thereby freeing the folded 80 blank. During the upward movement of the presser head, the forming plates are moved outwardly in readiness for a second operation.

Means including the blank-supporting 85 table are employed to apply a pressure to the folded edge of the cover, prior to the retraction of the wipers. To this end, the table-supporting frame 54, see Figs. 23 through 26, carries upon it, and beneath said 90 table 40, a pressure frame composed of a pair of laterally spaced parallel side bars 366. Parallel upper and lower bars 368 are slidably mounted on said side bars and are provided with grooves in which said side bars are received. Said bars 368 are provided with opposed dove-tailed grooves 370 in their upper faces in which corner blocks 372 are slidably received. Said corner blocks are provided with upstanding corner posts 374 having rounded corners which are located in the corners of the die frame and are notched to receive removable pressure bars 376, which bars, in cooperation 95 with said corner posts, define a continuous line of pressure. Said corner posts and pressure bars are located within the die frame immediately beneath the peripheral portion of the table and normally slightly therebelow. Said pressure bars and corner posts are adapted to be raised into pressure engagement with the table by the raising of the table-supporting frame 54 under the action of the cam ring 24 in a manner previously 100 described, thereby to press the table against the folded edge of the blank under the extended wipers.

The pressure frame is adjustable for various dimensions of blanks by sliding the bars 368 upon the bars 366 and by sliding the corner blocks 372 along the bars 368. Pressure bars 376 of suitable dimensions are adapted to be placed on the corner blocks for the particular type of blank to be folded.

The pressure frame is leveled and adjusted relative to the blank-supporting table by adjusting screws 378, which screws have a locking swivel connection in the lower end faces of said bars 366 as illustrated in Fig. 125 26 and are screw-threaded into the table 130

supporting frame 54 and extend therebelow to a position accessible beneath the bed of the machine. The pressure frame can be raised and lowered as a unit by rotating said screws, or any corner of the frame may be raised and lowered by rotating the screw associated with that corner.

The construction may be otherwise modified without departing from the spirit of the 10 invention.

I claim:

1. In a folding machine, an inclined bed, wipers carried by and inclined with said bed, a presser head disposed above and inclined with said bed, a driving unit including a horizontal drive shaft disposed at the rear of said bed, and inclined operating mechanism connecting said inclined wipers and presser head with said horizontal drive 20 shaft.

2. In a folding machine, an inclined bed, wipers carried by and inclined with said bed, a presser head reciprocably disposed above and inclined with said bed, inclined 25 actuating mechanisms for said wipers and presser head, and operating mechanism for said actuating mechanisms including inclined elements having operative connections with said actuating mechanisms.

3. In a folding machine, an inclined bed, wipers carried by and inclined with said bed, a presser head reciprocably disposed above and inclined with said bed, inclined actuating mechanisms for said wipers and 35 presser head, a reciprocable member having operable connections with said actuating mechanisms, and means including a horizontal drive shaft for reciprocating said member.

4. In a folding machine, an inclined bed, wipers carried by and inclined with said bed, a presser head reciprocably disposed above and inclined with said bed, inclined 45 actuating mechanisms for said wipers and presser head, a reciprocable member having operable connections with said actuating mechanisms, and also having a horizontally-extended cam roller, an actuating cam for said roller, and means including a horizontal 50 drive shaft having a driving connection with said cam.

5. In a folding machine, an inclined bed, wipers carried by and inclined with said bed, a presser head reciprocably disposed 55 above and inclined with said bed, inclined actuating mechanisms for said wipers and presser head, a reciprocable member having operable connections with said actuating mechanisms, and also having a horizontally-extended cam-follower, and means to reciprocate said member including a cam rotatable in a vertical plane for actuating said cam-follower.

6. In a folding machine, an inclined bed, 60 wipers carried by and inclined with said

bed, a presser head reciprocably disposed above and inclined with said bed, inclined actuating mechanisms for said wipers and presser head, and operating mechanism for said actuating mechanisms including a vertically-disposed, horizontally-reciprocable member having an inclined member at the upper and lower ends thereof operatively connected with said actuating mechanisms, and an intermediately-disposed, horizontally-extended cam-follower, and a rotatable cam-member disposed in operative relation with said cam-follower.

7. In a folding machine, an inclined bed, wipers carried by and inclined with said bed, 70 a presser head reciprocably disposed above and inclined with said bed, inclined actuating mechanisms for said wipers and presser head, and operating mechanism for said actuating mechanisms including a pair of vertically-spaced, horizontally-extended guide-rods, a member slideable on said rods and having inclined upper and lower extensions operatively connected with said actuating mechanisms, and also having an intermediately-disposed, horizontally-extended cam-follower, and a rotatable cam-member disposed in operative relation with said cam-follower.

8. An inclined-bed folding machine having folding elements including inclined wipers disposed to define a folding space, an inclined presser head reciprocable into and out of said folding space, and blank-gripping means to hold a blank in said folding space prior to the operation of said folding elements.

9. An inclined-bed folding machine having folding elements including inclined wipers disposed to define a folding space, an inclined presser head reciprocable into and out of said folding space, and means to hold a blank in said folding space prior to the operation of said folding elements, means under control of an operative to actuate said holding means, and means under control of said folding elements to render said holding means ineffective.

10. An inclined-bed folding machine having folding elements including inclined wipers disposed to define a folding space, an inclined presser head reciprocable into and out of said folding space, and operative-controlled, blank-gripping means arranged to hold a blank against said presser head prior to and during a part of the folding operation.

11. An inclined-bed folding machine having folding elements including inclined wipers disposed to define a folding space, an inclined presser head reciprocable into and out of said folding space, and means to hold a blank in the folding space prior to the folding operation having mechanism associated therewith constructed and arranged 130

to automatically release said holding means from holding engagement by the reciprocatory movement of said presser head.

12. In a folding machine, folding elements including a blank-supporting table, a presser head disposed above and reciprocable into and out of contact with said table, a blank-holding device disposed beneath said presser head and arranged to be elevated above said table to press a blank against said presser head when the presser head is in elevated position, and to be depressed by said presser head, and means to restrain said holding device in depressed position.
13. In a folding machine, folding elements including a blank-supporting table, a presser head disposed above and reciprocable into and out of contact with said table, a blank-holding device disposed beneath said presser head and arranged to be elevated above said table to press a blank against said presser head when the presser head is in elevated position and to be depressed by said presser head, and frictional means to restrain said holding device in depressed position.

14. In a folding machine, folding elements including a blank-supporting table, a presser head disposed above and reciprocable toward and away from said table, a blank-holding device disposed normally beneath said table and arranged to be moved upwardly therethrough to press a blank against said presser head, and to be moved downwardly by the operation of said presser head, and frictional means to hold said holding device releasingly in normal position.

15. In a folding machine, folding elements including wipers, a presser head reciprocable between said wipers, reciprocable forming plates carried by said presser head, operating mechanism therefor including a sliding member carried by and reciprocable with said presser head, and an actuating member for said sliding member having an operative connection with said sliding member in all positions thereof.

16. In a folding machine, folding elements including wipers, a presser head reciprocable between said wipers, reciprocable forming plates carried by said presser head, operating mechanism therefor including a sliding member carried by and reciprocable with said presser head, and an actuating member for said sliding member having an operative connection with said sliding member which admits of the reciprocatory movements of said sliding member while maintaining the connection between said members.

17. In a folding machine, folding elements including wipers, a presser head reciprocable between said wipers, reciprocable forming plates carried by said presser head, operating mechanism therefor including a sliding member carried by and reciprocable

with said presser head, a stationarily-supported sliding member for actuating the aforesaid sliding member, and a sliding connection between said members admitting of the reciprocatory movement of said presser head while maintaining the connection between said two sliding members.

18. In a folding machine, folding elements including wipers, a presser head reciprocable between said wipers, reciprocable forming plates carried by said presser head, operating mechanism therefor including a sliding member carried by and reciprocable with said presser head, a stationarily-supported sliding member for actuating the aforesaid sliding member, and a sliding connection between said members including interlocking tongued and grooved members connecting said two sliding members and arranged for relative sliding movement in the plane of reciprocation of said presser head.

19. In a folding machine, folding elements including wipers, a presser head reciprocably disposed above said wipers, extensible and retractable forming plates carried by said presser head, and operating means for said forming plates including a reciprocatory member carried by said presser head above and between and common to all of said forming plates, and means including link-mechanism extended outwardly from said reciprocatory member and having pivotal connections both with said forming plates and with said reciprocatory member.

20. In a folding machine, folding elements including wipers, a presser head reciprocably disposed above said wipers, extensible and retractable forming plates carried by said presser head, and operating means for said forming plates including a reciprocating member disposed between said forming plates, and link-mechanisms connecting said forming plates and reciprocatory member including motion-reversing mechanism associated with some of said link-mechanisms, whereby to effect the extension of some and the simultaneous retraction of others of said forming plates.

21. In a folding machine, folding elements including wipers, a presser head reciprocably disposed above said wipers, an extensible and retractable forming plate carried by said presser head, and operating means therefor including a reciprocatory member carried by said presser head, and means to reciprocate said forming plate reversely with respect to the movements of said reciprocatory member including a lever pivoted intermediate its ends and having operative connections at its ends with said reciprocatory member and forming plate.

22. In a folding machine, folding elements including wipers, a presser head reciprocably disposed above said wipers, extensible and retractable forming plates car-

- ried by said presser head, and operating means for said forming plates including a reciprocatory member carried by said presser head and disposed between said forming plates, link and lever mechanism connecting said member and forming plates and arranged to expand and retract them together, a rod fixed to said reciprocatory member, a reciprocatory actuating member for said rod having a support independent of said presser head, and an interlocking sliding connection between said rod and actuating member.
23. In a folding machine, folding elements including extensible and retractible forming plates, wipers movable inwardly over said forming plates to wipe the edge of the material over the extended forming plates, and operating means for said forming plates including a locking member disposed in position to engage a component of said operating means and hold it against operative movement, whereby to hold said forming plates in extended position against the action of said wipers.
24. In a folding machine, folding elements including extensible and retractible forming plates, wipers movable inwardly over said forming plates to wipe the edge of the material over the extended forming plates, operating means for said forming plates including a cam-follower associated with said forming plates, a reciprocatory cam member for operating said cam-follower, and an automatically-operative locking cam-member carried by said reciprocatory cam-member and arranged automatically to move into position behind said cam-follower to hold it from effective operation, whereby to hold said forming plates in extended position against the action of said wipers during a part of the movement of said cam member.
25. In a folding machine, folding elements including wipers, extensible and retractible forming plates associated with said wipers, and operating means for said forming plates including a cam-follower, and a reciprocable cam block in which said cam-follower is adapted to operate, said cam block having a shiftable cam-wall arranged to be displaced out of normal position by said cam-follower during a movement of said cam block, and means to restore said shiftable cam-wall to normal position.
26. In a folding machine, folding elements including wipers, extensible and retractible forming plates associated with said wipers, and operating means for said forming plates including a cam-follower, a reciprocable cam block having a cam slot in which said cam-follower is received, and a sliding member disposed in said slot and having an inclined face comprising a wall of said slot, said sliding member adapted to be displaced out of a normal position in said slot by said cam follower, and means to return said sliding member into normal position and behind said cam-follower, whereby to hold said forming plates in extended position against the wiping action of 70 said wipers.
27. In a folding machine, fixed parallel guide-ways, a presser head reciprocable in said guide-ways, a lever supporting said presser head at one end, and lever-reciprocating means engageable with the free end of said lever including a slide block connected with the free end of said lever and having a cam-follower, and a cam-member movable transversely of said slide block in 75 operative relation with said cam-follower.
28. In a folding machine, a bed having fixed parallel guide-ways, a presser head reciprocable in said guide-ways, a lever supported by said bed and having a pivotal connection with said presser head at one end, and means to reciprocate said lever including a block vertically slidable on said bed and having a pivotal connection with the free end of said lever, and also having a cam-follower, and a cam-member movable transversely of said block in 80 operative relation with said cam-follower.
29. In an inclined-bed folding machine, an inclined bed having inclined and parallel guide-ways, a presser head reciprocable in and inclined with said guide-ways, a lever carried by said bed above said presser head and having a pivotal connection therewith at one end, an inclined slide-block carried by said bed and having a pivotal connection with the other end of said lever, and also having an inclined cam-follower, and a vertically disposed, horizontally-reciprocable member having an inclined cam-block disposed in operative relation with said cam-follower.
30. In a folding machine, a presser head, forming plates carried thereby, a post carried dependingly by said presser head between said forming plates, and a presser plate carried by the lower end of said post.
31. In a folding machine, a presser head, forming plates carried thereby, a post carried dependingly by said presser head between said forming plates, and a presser plate disposed beneath said forming plates and having a detachable connection with the lower end of said post.
32. In a folding machine, a presser head having a guide slot, a forming plate carrier reciprocable in said slot and having a guide-way on its lower face, a block slidable on said guide-way and having a guide-way on its lower face transversely disposed with respect to said first guide-way, a forming plate slidably received on said second guide-way, and means to secure said carrier, block and forming plate fixedly together.
33. In a folding machine, a die-frame

composed of superimposed and transversely-disposed bars bounding a folding space, filler-bars disposed over said lower bars and having their upper surfaces terminated approximately in the plane of the upper surfaces of said upper bars, wipers reciprocable over the upper faces of said bars, and a presser head reciprocable into and out of said folding space.

34. In a folding machine, a die-frame composed of superimposed and transversely-disposed bars arranged to bound a rectangular folding space, filler-members disposed over the lower bars between said upper bars and extended upwardly to about the level of the upper bars, wipers reciprocable over the upper faces of said bars, and a presser head reciprocable into and out of said folding space.

35. In a folding machine, an adjustable die frame composed of superimposed, transversely-disposed bars arranged to bound a rectangular folding space, supporting-members for said bars on which said bars are movable toward and away from each other, filler members removably disposed over said lower bars and extended upwardly to about the level of said upper bars, wipers reciprocable over the upper faces of said bars, and a presser head reciprocable into and out of said folding space.

36. In a folding machine, a die-frame defining a folding space having straight sides terminated in the same top plane and a round corner, and a detachable corner block carried by said frame and shaped and disposed to define the round corner, and having its upper face terminated in the aforesaid top plane, and wipers disposed in a common plane immediately above said sides and corner blocks and movable thereover into said folding space.

37. In a folding machine, a die frame defining a folding space having straight sides and round corners and composed of superimposed, transversely-disposed bars, detachable corner blocks carried by the lower bars adjacent the upper bars and shaped and disposed to define the round corners of the folding space, said blocks having grooves in their upper faces, filler-bars removably received in said grooves, wipers reciprocable over the upper faces of said bars, and a presser head reciprocable into and out of said folding space.

38. In a folding machine, a die-frame defining a folding space, wiper-carriers reciprocably carried by said frame, wipers secured to said carriers, and a presser head reciprocable into and out of said folding space between said wipers.

39. In a folding machine, a die-frame defining a folding space, wiper-carriers reciprocably carried by said frame, wipers disposed upon said carriers, means removably

securing said wipers and carriers in the aforesaid relation, and a presser head reciprocable into and out of said folding space between said wipers.

40. In a folding machine, a die-frame defining a folding space and having slide-grooves in its upper face, wiper-carriers slidably received in said grooves, wipers disposed upon and attached to and carried by said carriers, and a presser head reciprocable into and out of said folding space between said wipers.

41. In a folding machine, means to define a folding space, a wiper reciprocable into and out of said space, and means to reciprocate said wiper including a reciprocable slide block, and means adjustably connecting said wiper rigidly with said slide block.

42. In a folding machine, means to define a folding space, a wiper reciprocable into and out of said space, and means to reciprocate said wiper including a reciprocable slide block, an adjustment-block having a sliding connection with said slide block, and a bracket having a sliding connection with said adjustment block and a connection with said wiper.

43. In a folding machine, means to define a folding space, a wiper reciprocable into and out of said space, and means to reciprocate said wiper including a reciprocable slide block, an adjustment-block having an interlocking sliding connection with said slide block, and a bracket having a connection with said wiper and an interlocking sliding connection with said adjustment-block.

44. In a folding machine, a die frame defining a folding space, a wiper-carrier reciprocable in said frame, a wiper attached to said carrier and extended over said frame, and means to reciprocate said wiper including a reciprocable die block disposed beneath said wiper, an adjustment-block having a sliding interlocking connection with said slide-block, and a bracket having a connection at its upper end with said wiper-carrier and at its lower end a sliding interlocking connection with said adjustment block.

45. In a folding machine, means to define a folding space, a wiper movable into and out of said space, means to reciprocate said wiper including a reciprocable slide block, and means connecting said wiper and slide block having connections with said wiper and slide block which are adjustable in different directions.

46. In a folding machine, means to define a folding space, a wiper movable into and out of said space, and means to reciprocate said wiper including a reciprocable slide block, an adjustment-block having provision for adjustment along the length of said slide block and having means connecting it with said wiper for relative transverse-adjustment therebetween.

47. In a folding machine, a reciprocable wiper, a reciprocable slide block for operating said wiper, an adjustment-block having provision for adjustment-movement along the length of said slide block and having a slot therein which is extended transversely of the line of movement of said slide block, and a bracket adjustably received in said slot and having a connection with said wiper.
48. In a folding machine, a reciprocable wiper, a reciprocable slide block for operating said wiper, said wiper disposed above and having provision for adjustment transverse of the plane of movement of said slide block, and means operatively connecting said slide block and wiper in any position which said wiper may occupy.
49. In a folding machine, a die frame defining a folding space and composed of a pair of spaced parallel bars at least one of which has a support on which it is mounted for adjustment toward and away from the other, and cross-bars carried solely by the aforesaid bars and having adjustable connections therewith by which they are movable toward and away from each other.
50. In a folding machine, a bed, a die frame disposed above said bed and composed of a pair of spaced horizontal bars, and cross-bars extended over and having adjustable connections with said horizontal bars, at least one of said horizontal bars having an adjustable connection with said bed by which it can be moved toward and away from said other horizontal bar, said connection comprising brackets depending from the ends of said bar and slidably received in guide-slots formed in said bed and extended transversely of said bar, and means to clamp said brackets in adjusted position in said slots.
51. In a folding machine, a bed, and a die frame including spaced horizontal bars disposed above said bed and adapted to support folding elements, said bars having depending brackets on the ends thereof which are slidable in aligned guide-slots in said bed, and means to clamp said brackets in adjusted position in said slots.
52. In a folding machine, a bed, and a die frame including spaced horizontal bars disposed above said bed and adapted to support folding elements, said bars having depending brackets on the ends thereof which are slidable in aligned guide-slots in said bed, means to clamp said brackets in adjusted position in said slots, and cross-bars carried wholly by said horizontal bars and having provision for adjustment along the lengths thereof.
53. In a folding machine, a bed, folding elements including wipers disposed above said bed, and operating means therefor including slide blocks having connections with said wipers, a plurality of posts disposed in concentric rows rising from said bed, and an oscillatory cam ring received between said rows and having operative connections with said slide blocks.
54. In a folding machine, a bed having concentric rows of radially-aligned posts rising therefrom, a cam ring disposed for oscillatory movement in the circular space between said rows of posts, said posts having aligned grooves in their upper faces, slide blocks extended over said cam ring and received slidably in said grooves and having operative connections with said cam ring, and folding elements having operative connections with said slide blocks.
55. In a folding machine, a blank-supporting table, folding elements associated with said table, an oscillatory cam-ring disposed beneath said table and a reciprocatory supporting frame for said table disposed above and having an operative connection with said cam ring.
56. In a folding machine, a blank-supporting table, folding elements associated with said table, an oscillatory cam-ring disposed beneath said table and a reciprocatory supporting frame for said table disposed above and having depending lugs which surround said ring, and cam followers carried by said lugs disposed in inclined cam slots in the periphery of said cam ring by which said frame is raised and lowered.
57. In a folding machine, a forming plate having angularly-related thin sections over the edges of which the material is adapted to be folded and having a region of increased thickness at the junction of said sections adapted to receive and lie under the corner-fold of the material.
58. In a folding machine, folding elements including a forming plate having angularly-related folding edges connected by a round corner, and having a region of increased thickness at the corner, and a corner wiper adapted to move over the round corner and the region of increased thickness and to fold the corner of the material over said region of increased thickness.
59. In a folding machine, an inclined bed, an inclined oscillating cam ring disposed on said bed, and having peripherally-disposed inclined gear teeth, and a horizontally-reciprocable actuating member for said ring having an inclined rack meshing with the inclined gear teeth of said cam ring.

In testimony whereof, I have signed my name to this specification.

JOSEPH W. ANTHONY.
